SAFETY RAZOR

Filed Sept. 18, 1931

Inventor
JOSEPH BORNEMANN

By
Nathan Levin
Attorney

UNITED STATES PATENT OFFICE

JOSEPH BORNEMANN, OF TRENTON, NEW JERSEY

SAFETY RAZOR

Application filed September 18, 1931. Serial No. 563,471.

The principal object of my invention is to provide a safety device which is readily, easily and securely attachable to the well known razor of the straight type in common use today. Another object of my invention is to provide a safety device of the character described which will absolutely preclude the possibility of cutting ones self when shaving with a straight razor to which my safety device has been attached, even when the arm is given a sudden movement.

Another object of my invention is to provide a body formed of one piece of spring material by means of which the guards of the safety device may be secured and positioned in the proper relationship to the razor edge. Still another object of my invention is to so mount the guards mechanically, that the planes of the guards will constantly be parallel to each other and to the plane of the razor, also so that the edges of the guards, which are equally spaced on each side of the razor will at all times be equally distant from the razor edge, despite the angle of the parallelogram of which the guards form opposite sides.

Further objects and advantages will appear in the following description in which like characters designate like parts and in

which:

Fig. 1 is a view of the safety device on a straight razor shown in dot and dash lines,

Fig. 2 is an end view in the direction of 2-2 of Fig. 1,

Fig. 3 is an end view in the direction of 3-3 of Fig. 1,

Fig. 4 is a plan view of the body member before it is bent to shape,

Fig. 5 is plan view of one of the guard members,

Fig. 6 is an end view of Fig. 5, and

Fig. 7 is a view on line 7-7 of Fig. 1 showing the device in operation.

In the drawing the straight razor is shown 45 in dot and dash lines at 1, the handle not be-

ing shown. This razor has a body 2 and the edge 3, the contour of which is similar to the edge 4 of the guards 5, and coincides therewith in Fig. 1. The safety device has the metal body member 6 made of a single 50 shaped piece of suitable spring material as is clearly shown in Fig. 4 before bending on lines 7'-7'. In the center is the rectangular opening 8, through which the razor projects. The body member 6 has projecting lugs at 9, 10, 11, 12, 13 and 15; cut out portions at 14, 18, and 19; a small hole at 17; and a projecting tab 16 for purposes to be described. The body member 6 is folded upon line 7'-7' to substantially V-shape as is 60 shown in cross-section in Fig. 3, the pairs of lugs 9, 10, and 11, 12, together forming projecting studs or fixed pivots for members to be described. The fold lines 20 and 21 form stops for the razor, and the sides of the 65 body 6 form spring clamps around the body 2 of the razor as shown in Fig. 7 to securely hold the device in position. Covering the front end of the V-shaped body is the tab 16 bent over to position, the lug 15 bending 70 over the opposite side of the body to secure the parts. Likewise lug 13 bends over the opening 14 in the opposite side of the body as appears in Fig. 3.

Side members or guards 5 are each formed 75 of a blank of suitable material as shown in Fig. 5, with the wires 22, and 23 in place to be secured into position. The end 24 of the projection 25 is rolled or wrapped about wire 22 to secure it in position so that the projecting end may serve as a pivot as appears in Fig. 6. In a similar manner the tab 26 secures the wire 23 in position, this wire having two projecting ends that serve as pivots. The guards 5 are secured to each other by 85 means of similar cross members 27, 28, and 29 which are drilled to receive the projecting ends of the wires 22 and 23 in a loosely jointed connection. Thus it will be seen that on one end of the body 6 the two arms 25 and the 90

members 27 and 28 form a four sided loosely jointed parallelogram. The member 27 has a pin 29 in it which projects inwardly into the hole 17 in the tab 16; the member 28 rocks on the pivots formed of lugs 9 and 10; and the member 29 rocks on the pivots formed of lugs 11 and 12. It is to be understood that the wires 23, 23 are secured at each end in the members 28 and 29 to prevent endwise accidental removal of said members, and the guards 5, 5 pivot about the wires 23, 23.

The openings 18 and 19 provide clearance for the wires 22, 22, when the device assumes the position of Fig. 7.

15 The depending portions 30, 30 of the guards 5, 5 have the contour of line 4 which is the exact contour of the razor edge, and this may change with a change in contour of the razor.

20 It will be seen, as in Fig. 7, that due to the stationary pivots provided respectively by studs 9 and 10, 11 and 12, and 29 and the loose pivots at 22, 22 and 23, 23, the planes of the guards 5, 5 will always be parallel to each other, and will always be parallel to a plane drawn through the fixed pivots, in which lies the edge of the razor, so that the bottom edges of the guards will constantly be equally spaced from the edge of the razor regardless 25 of the angle that the parallelogram assumes as the razor is used as appears in Fig. 7, the edges of the guards preventing the edge of the razor from cutting since the three edges constantly remain wholly within a single plane.

30 It is to be understood that while I have herein shown a preferred embodiment of my invention, it will be obvious to those skilled in the art that various forms and 35 modifications may be made without departing from the spirit of the invention shown and hereafter set forth in the appended claims.

I claim:

40 1. In a safety device for razors, a body member for attachment to a razor blade said body member having pivots at each end adjacent the back and the edge of the blade, supporting members rockable on said pivots, and guard members pivotally mounted on said supporting members parallel to the median plane of the blade at a sufficient distance therefrom to permit the guard members to swing freely for automatically guarding either side of the blade, the lower edge of the guard members being at all times substantially in the same plane as the edge of the razor blade.

45 2. In a safety device for razors, a resilient clip adapted to be held on a razor blade, guard members at opposite sides of the razor the lower edges of the guards being parallel to the edge of the razor, and a parallel linkage system for connecting the guards to the clip and to each other in free swinging relation,

whereby the guards move automatically to protect either side of the razor.

3. In a safety device for razors, a pair of guards, a support for holding the guards at opposite sides of a razor blade, and a parallel linkage system on the support for maintaining the guards in free swinging relation to the razor blade with their lower edges at all times approximately in the same plane as the cutting edge of the razor blade.

75 In testimony whereof, I affix my signature.

JOSEPH BORNEMANN.
